COAT HOOK

Application filed May 10, 1929. Serial No. 362,076.

This invention relates to coat hooks in general, and particularly to that type of coat hooks which are used in connection with sheet metal lockers and cabinets.

5 The object of the invention is to provide new and improved hooks which can be assembled in a locker with a minimum amount of labor and a maximum amount of security.

Another object is to provide an improved 10 construction for coat hooks and the like which will require but a single hole in the partition upon which the hook is mounted without sacrificing any of the rigidity and which will maintain the hook in proper rigid position.

Another object is to provide a hook having 15 complementary lugs and recesses so that when a pair of hooks is arranged back to back the lugs on one hook will nest in the recess of another hook.

Another object is to provide a coat hook 20 which has an outturned lug or projection so that a pair of the hooks may be placed back to back, and the lugs inserted in a slot or recess 25 in the locker ceiling and maintained in proper rigid position by the use of a single fastening means passing through the body of the hooks.

A further object is to provide an improved 30 coat hook which has an upstanding outturned lug or projection and complementary lugs and recesses so that a pair of hooks may be located on opposite sides of the wall or they may be inserted in a slot or recess of the ceiling of the locker and then held in position by 35 means of a single tightening means.

A still further object is to provide a universal coat hook which may be singly fastened to the wall of a locker, which is provided with means so that exact duplicates of the hooks may be applied back to back and selectively fastened to the side walls or the ceiling of the locker, and which employs the use of but a single tightening means for securely maintaining the hooks in proper rigid 45 position regardless of the manner in which they are applied to the locker.

Other objects and advantages will herein-after appear.

The invention comprises in general a coat 50 hook having a flattened base which is provid-

ed with a single hole to receive the tightening means. Complementary lugs and recesses are arranged on the back face of the base so that they will distort the metal and cause indentation when the single tightening means is drawn up. An upstanding outwardly extending projection is arranged at the top of the base, and it has its inner contacting or rear face rounded or cammed. A pair of hooks may be fastened to the ceiling of a locker by inserting the projections in a slot and with the aid of a single tightening means will cause the hooks to be maintained in proper rigid position in the slot. The complementary lugs and recesses prevent movement of one hook relative to the other.

In the accompanying drawing which illustrates a selected embodiment of the invention the views are as follows:

Fig. 1 is a detail sectional view on the line 1-1 of Fig. 2 and shows a pair of hooks applied to the ceiling of a locker.

Fig. 2 is a detail view on the line 2-2 of Fig. 1.

Fig. 3 is a detail top plan view.

Fig. 4 is a sectional view on the line 4-4 of Fig. 1.

Fig. 5 is a detail perspective view of two 80 of the hooks showing the complementary lugs and recesses.

Fig. 6 is a side view showing the manner in which the hook may be applied to the side wall of a locker.

Fig. 7 is a rear view of the hook shown in Fig. 6.

Referring to the drawing, 8 designates a coat hook having a base 9 provided with a hole 10. The hook is preferably made of cold rolled metal and has the base thereof flattened by hammering or the like, so that the entire hook may be forged instead of cast. On the inner side 11 of the base 9, that is, on the side which will contact with the partition, there is provided a lug 12 and a recess 13. Fig. 5. The lug 12 is located the same distance from the hole 10, and on the opposite side of it, as the recess 13 is located from the hole. The lugs and recesses are counterparts of each other, with the result

that when the hooks are brought back to back, that is, with their bases in contact, the holes 10 in each hook will be in alignment, and the lug on one hook will fit into the recess in the other. Thus it may be said the hooks mate with each other or interfit, the lug and recess being symmetrically placed with reference to the hole in the base. The result of this construction is that when two hooks are placed on opposite sides of the partition Fig. 6 and a bolt 14 is inserted in the hole 10 and in a hole in the locker, the nut 15 will cooperate with the head 16 of the bolt and cause the lug to indent the metal of the partition and force it to a greater or less extent into the recess 12 of the opposite hook. The two hooks are thus drawn up tight and the lugs 13 will seat in the recesses 12 and prevent the hooks from rotating about the bolt as an axis.

A lug or projection 17 is arranged on the upper end of the base and has its inner face rounded at 18 and its outer face provided with a notch 19; so that a pair of the hooks 23 may be easily inserted through a slot or an opening 20 in the top wall or ceiling 21 of the locker.

If the locker is to be placed under some object so that it is necessary to keep the top of the locker flush, the top may be provided with a depression 22 as clearly shown in Figs. 1 to 3. A washer or other reinforcing member 23 may be placed in the depression 22 and it is preferably made the same size as the depression and in such a manner that the washer will not rotate therein, Fig. 3. The projections may be provided with beveled surfaces 24 to permit the projections to be easily inserted in the slot 20. If the reinforcing washer 23 is used it is, of course, also provided with a slot 25 which is preferably substantially the same size as the slot 20. The result of this construction is that when two hooks are inserted in the slot in the ceiling the outer edges of the projections will be forced against the material at the sides of the slot, and prevent the hooks from pulling out of the slot or from moving laterally. The complementary recesses and lugs on the hooks will prevent one hook from moving relative to the other. The single tightening means holds the two hooks together as well as causing the binding action of the projections against the sides of the slots.

In practice a pair of the hooks is arranged back to back and then spread apart so that the lugs of the rounded surfaces 18 contact. The projections 18 can therefore be readily inserted in the slot 20 or slots 20 and 25, as the case may be. As the hooks are brought together, the notches 19 formed by the outward bending of the projections will be forced to bind against, and grip the sides of the slot in the ceiling or washer. When the

bolt 14 is inserted in the holes 10, and the nut 15 tightened, the outwardly extending projections will further this binding action, and the complementary lugs and recesses will nest.

The invention provides means whereby a single coat hook may be applied to the side wall of a locker, or a pair of coat hooks may be applied to opposite sides of the locker wall or to the ceiling and secured in proper rigid position by means of a single bolt. Regardless of the positioning of the hook or the manner in which it is applied, a single type of hook is applicable for use whether singly, or in pairs spaced back to back and fastened to the ceiling or the side walls of the locker.

Changes may be made in the form, construction, and arrangement of the parts without departing from the spirit of the invention or sacrificing any of the advantages thereof, and the right is hereby reserved to make all such changes as fairly fall within the scope of the following claims:

The invention is hereby claimed as follows:

A universal hook member comprising a base having a hole therein, a hook integral with said base, a lug or projection on said base, a base member having a hole therein, a lug or projection on said second base member, each of said bases having their outer ends provided with a notch for receiving a member for ceiling hanging, complementary recesses on said base members for engaging said projections, and a single fastening means passing through said holes.

In witness whereof, I have hereunto subscribed my name.

WALTER N. VANCE.

In witness whereof, I have hereunto subscribed my name.

JOSEPH RATZ.
